SEPARATION OF OXYGEN, NITROGEN, AND ARGON FROM AIR

Application filed July 3, 1930, Serial No. 465,772, and in Germany February 8, 1930.

The invention relates to a process for obtaining oxygen and nitrogen by a two-stage rectification of liquid air with the simultaneous production of argon in a third rectifying column.

For the separation of argon from the air, the major portion of the nitrogen is first separated and the residue consisting principally of oxygen and argon is separated into pure oxygen and a mixture rich in argon by a further rectification. The heat-interchange necessary for effecting the latter rectification is obtained by means of a cycle either of nitrogen, with indirect heating or cooling of the column, or of argon, with direct exchange.

The present invention makes possible a considerable simplification and reduction of expense in the production of argon in connection with the two-stage rectification of air. In the first stage nitrogen is obtained under a pressure which is sufficient to permit its condensation in the oxygen-rich liquid in the lower part of the argon rectification column. In the process of the invention a portion of the nitrogen is withdrawn from the first column in the gaseous state and utilized for heating and cooling the argon column. Hitherto this nitrogen, insofar as it was not returned in the liquid state to the first rectification column, was utilized for washing oxygen out of the nitrogen vapors in the second rectification column, and as much nitrogen as was available was used for this purpose in order to make the washing operation as complete as possible. The withdrawal of nitrogen for use in the argon column has heretofore been considered to be incompatible with the obtaining of a high yield of oxygen or the production of a practically pure nitrogen.

In the process of the invention a part of the oxygen-rich mixture is reworked in the argon column. At the same time the first column is operated to produce a fraction containing a high percentage of nitrogen, and in the second column the rectification is improved by increasing the plate number or effect. It was found that the withdrawal of argon from the second column promotes the

separation of oxygen and nitrogen, and compensates the unfavorable effect of diminishing the amount of washing liquid.

By way of illustration, one method of carrying out the invention will be described with reference to the accompanying schematic drawing.

In the drawing, 1 and 2 are the two rectifying columns of a two-stage rectifier, such as is commonly used for the production of oxygen and nitrogen. 3 is the argon rectification column, the argon-oxygen mixture being introduced through pipe 4. The pressure column 1 contains a sufficient number of plates that nitrogen containing 1% or less of oxygen is obtained at the upper end. The second column is made so large that it has the effect of fifteen ideal rectification plates. In this way the nitrogen vapor may be purified to a content of oxygen of about 2%.

For heating the argon column a part of the nitrogen is withdrawn in the gaseous state from the nitrogen condenser 5 or below it, at the pressure of about five atmospheres existing in column 1 and is liquefied in coil 6 of the argon vaporizer 7. The liquid nitrogen is then expanded through valve 8 into condenser 9 as a cooling means for the condenser. The vaporized nitrogen leaving 10 can be conducted, together with the nitrogen leaving the second column at 11, to a counter current heat exchanger (not shown).

In the method of operation herein described only a part of the oxygen obtained in column 2, for example one-half, is introduced into the argon rectifying column 3. If column 2 is operated to produce an oxygen of over 99% in purity, as is demanded by present industrial requirements, very little argon would be obtained by the further working of this oxygen. Therefore, in the process of the invention the oxygen to be treated in the argon column is withdrawn from a higher portion of column 2 where the oxygen content of the liquid is between 90 and 98%. In the lower part of column 3 this oxygen is brought to the same or a higher purity as that produced in column 2. The lower parts of the two columns therefore operate in parallel with reference to the liquid. With this

method of operation it is possible to withdraw at 12 a substantial proportion of the argon content of the air, in the form of a mixture containing 50% to 90% of argon.

5 Thus the process of the invention affords a simple method of simultaneously obtaining from the air practically pure oxygen, nitrogen and argon.

In the same way the process is generally 10 applicable to the separation of ternary mixtures, where the argon is represented by a gas of intermediate boiling point,

We claim:

A process for the production of argon, oxygen and nitrogen by the low temperature rectification of air which comprises subjecting liquid air to two stages of rectification, operating the first stage to produce a fraction containing a high percentage of nitrogen, 15 withdrawing only a portion of the oxygen-argon mixture in liquid form from the second rectification stage at a point where the oxygen content of the liquid is about 90 to 98%, introducing said oxygen-argon mixture into 20 the middle portion of a further rectification column, and subjecting said oxygen-argon mixture to further rectification, the mixture being heated by the liquefaction of a portion of the gaseous nitrogen fraction from the first 25 stage and being cooled by the evaporation of the nitrogen thus liquefied, high percentage oxygen being obtained at the bottom of said further rectification column.

In testimony whereof, we affix our signatures.
